PRECISION ROLLING DISK COLTER

Paul Stoner, Valparaiso, Ind., assignor of fifty per cent to Ruth Stoner and fifty per cent to Catharine Stoner, both of Valparaiso, Ind.

Application June 6, 1940, Serial No. 339,155

4 Claims. (Cl. 97—209)

My invention relates to improvements in precision rolling disk colters and it more especially relates to the features pointed out in the annexed claims.

The purpose of my invention is to provide a rolling disk colter that is rigidly attached to a plow beam at an angle that is definitely and positively micrometrically changeable; that avoids side drafts; that has a relatively narrow cut; that in practice is not clogged by tall weeds, soy beans, corn stalks, combined straw or other growths; and that is equally adapted to a single or multiple bottom plows. The structure avoids the complexities that have hitherto characterized the use of rolling disk colters.

With these and other ends in view I illustrate in the accompanying drawing such instances of adaptation as will disclose the broad idea of the invention without limiting myself to the specific details shown thereon and described herein.

Fig. 1 is a front elevation looking toward the rear.

Fig. 2 is a top plan view partly in section of Fig. 1 in an enlarged relation.

Fig. 3 is an enlarged side elevation.

Fig. 4 is an elevation of a micrometric adjustment plate.

Fig. 5 is an enlarged plan view of the adjusting features of Fig. 2 partly in section.

Fig. 6 is a top plan view in section on the center line of a modified form of clamping bolt.

Fig. 7 is a miniature side elevation.

In practicing my invention, I may use whatever equivalents or modifications of structure that the exigencies of varying conditions may demand without departing from the broad spirit of the invention.

On a plow beam 1 I attach a rigid vertical support 2 by means of a clamping plate 3 and a suitable U-bolt 4. This support is offset at 5 to produce greater rigidity. At the lower end 6 of the support, there is attached an integral extension 7 from the bearing 12 by means of bolts 8. Between the bar 7 and the lower end 6 of the support 2 I place a micrometric adjusting member 9 which gives the desired horizontal cant to the rolling colter 10. It is held rigidly by bolts 8 that pass through it and when the bolts are tightened it will remain unchanged, and will hold the front half 11 of the colter 10 approximately parallel with the furrow that is being made by the plow. This avoids side draft and reduces the power required to move the colter through the earth in advance of the plow.

The colter 10 is mounted in a bearing 12 of any desired type. As exemplified, it has an upstanding extension 7, by means of which it is attached to the vertical support 2 by bolts 8. The micrometric member 9 is placed between 6 and 7. It is secured in place by through bolts. The member 9 comprises a head portion that may be approximately square in cross section and a thin plate 13 attached to it. The thin portion 13 has elongated slots 14 for the through bolts 8. This thin portion, at 15, forms a pinless pivot point.

As shown in Fig. 5, the adjustment of the member 9 between the parts 2 and 7 is extremely delicate. Hitherto the basic feature of a delicate and positive adjustment that the position of the colter shall hold to the furrow that is being plowed has not been understood. A relatively large movement of the member 9 between the parts 6 and 7 produces only a slight change in angle of the colter.

The prior horizontal canting of rolling disked colters has been so extreme as to produce excessive side draft, needless depth and width of cut. My structure avoids annoying clogging that has been encountered heretofore. These disadvantages are entirely overcome by my positively rigid construction. I have found in actual practice that my present form of colter construction is an advance over previous efforts that have been directed toward improvements in this field.

The bearing 12 is provided with a recess at each end in which ring carriers 16 for balls are placed. On the inside of the bearing there is a tube 17 which extends from the inner retaining ring of the ball bearing at one end to the other at the other end of the bearing. The inner ball rings are positioned on a tubular extension 18 of the disk 20 provided with a square hole therethrough for the square colter pin 19. At the right hand end of the bearing, Fig. 2, there is a dust disk 20. This engages the adjacent inner ball race ring and its tubular extension 18 receives the inner ball race ring at the other end.

Next to the part 20 the disk 10 is placed. Following this, there is a clamping disk 21. A square head 22 of the bolt 19 is recessed in the disk 21. The parts 20, 10 and 21 have square openings. At the other end of the pin 19 there is a reduced left-hand thread diameter 23, a nut and a clamping washer 24 which abuts the adjacent inner ball bearing ring. This arrangement clamps the washer 24 and the disk 20 against the tube 17. A dust guard 25 may be placed adjacent the washer 24 and the end of the bearing 12.

As shown in Fig. 5 the bolts 8 are bent. As

shown in Fig. 6, the bolts 28 may be made straight, and a semi-spherical recess 26 formed in the support 2 associated with a washer 27 will adapt the bolt to whatever slight changes that may be produced during the shifting of the micrometric member 9.

By forming the bearing 12 and the upstanding portion 7 rigidly together as a unit, there is only one place in the entire arrangement that adjustments of the most delicate order are made, that is the relation that the member 9 bears to the parts 2 and 7.

I attain unusual results through the use of absolutely rigid connections throughout which hold the colter at an approximately horizontal angle of ten degrees. The position of the colter on the plow beam may be such that the center of the colter is about vertically above the front end of the plow share. Contrary to previous usage I only set the colter to about one-half more or less of the furrow depth and instead of turning over a width of ground by the colter, approximately the width of the furrow, I only use a narrow width, approximately one-fourth the width of the furrow. It is the rigid relation of the cant to which the colter is set to the depth and width of cut that secures my exceptional result.

If desired, I may make one or two standard sized members 9. In any event the slotted openings 14 are used to prevent the member 9 from being disassembled and lost from off the bolts 8. In practice it rarely may be necessary to exchange the parts 9 for other sizes because of the great delicacy and positiveness of its adjustment. The depth to which the colter will enter the ground is governed by the up and down adjustment of the support 2 on the plow beam.

What I claim is:

1. In disk colter plow attachments, a plow

beam, a vertical depending support rigidly held on the plow beam, an offset in the support, a rolling disk colter, a bearing for the colter, an integral extension from the bearing, means for supporting the extension on the depending support, a micrometric adjusting member between the extension and the support, said member comprising an enlarged head, a thin plate projecting therefrom, said plate having slotted openings, and bolts passing through the extension, the support and the slots of the plate for holding the parts in the desired rigid assembled relation.

2. A micrometric adjustment member comprising a relatively thin plate, one edge of the plate having a relatively minimum dimension, and an enlargement along the other edge of the plate of a relatively maximum dimension said plate having slotted openings therein.

3. In rolling colter attachments for plows, a bearing for the colter, an integral extension from the bearing, a depending support from the plow beam having an offset formed thereon, a pinless pivot at one edge of the extension and the support, means at the other edge of said parts for micrometrically positioning the edges with a non-contacting space-area therebetween, and means for rigidly holding the parts assembled subject to change as desired whereby the parts are held in rigid unchanging position after adjustments thereof have been made.

4. A micrometric adjusting plate of relatively rectangular shape comprising a maximum thickness throughout its length along one edge and extending over a minor portion of its width, and a minimum thickness throughout a major portion of its width so as to constitute minimum and maximum bearing faces whereby the minimum thickness edge forms a pivotal plane.

PAUL STONER.
